J. C. NEVIUS

CABLE CLAMPING DEVICE FOR GUARD RAILS

Original Filed Jan. 8, 1925

Inventor:

John C. Nevius
Alexander D. Bell
Attorneys.

UNITED STATES PATENT OFFICE.

JOHN C. NEVIUS, OF TRENTON, NEW JERSEY.

CABLE-CLAMPING DEVICE FOR GUARD RAILS.

Application filed January 8, 1925, Serial No. 1,210. Renewed April 27, 1927.

This invention is an improvement in cable clamping devices for clamping cable guard-rails against the rail posts, and one object of the invention is to provide novel clamping devices for what I term a "flush-face" cable guard-rail, especially adapted for use along the curves or dangerous portions of automobile highways, and the like, by the use of which devices the cable is positively supported at each post, or at as many posts as desired.

Another object of the invention is to provide novel devices for clamping the cables to the posts, in which no parts of the devices project into the vertical plane tangent to the edge of the cable opposite the posts, so that if a vehicle collides with the cable guard-rail the rail will not only shunt the vehicle back onto the roadway, but will prevent the vehicle, as it slides along in contact with the guard-rail, from coming in contact with the posts or parts of the cable clamps, and thus prevent the vehicle from being brought to a violent, sudden stop.

In the usual construction of cable guard rails, the cables are generally passed through bores in the fence posts, or if clamping devices are used to support the cables on the posts, such clamps, heretofore designed, have had portions projecting into and beyond the vertical plane tangent of the edge of the cable opposite the fence posts. In either case an obstruction is presented which is likely to do additional damages to a vehicle side-swiping the guard rail, by the impact of parts of the vehicle against the protruding portions of the fence posts or clamps. My novel clamps eliminate the possibility of the vehicle touching either the posts or cable clamps.

Other objects of the invention are, to provide novel cable clamps for guard rails, by the use of which openings may be left in the guard-rail at any place, and of any desired width; the fence posts may be replaced at any point without interference with any other parts of the guard rail; the strain on the cable is equally distributed throughout the entire line of posts, thereby developing the full strength of the cable; the guard rail may be quickly erected by inexperienced men and the maintenance will be negligible; furthermore, the erection of the guard rail will require no cable bores in the posts, no

"dead men," or "pull-offs," no eye-bolts, 55 spreaders, braces, or the like, and the clamps may be readily attachable to either round or square posts; and the construction is inexpensive, and will embody the desired feature of economy, stability, durability, and flexibility.

I will explain the invention with reference to the accompanying drawing which illustrates practical embodiments thereof to enable others to adopt and use the same, and will summarize in the claims the novel features of construction and novel combinations of parts, for which protection is desired.

In said drawings;

Fig. 1 is a top plan view showing my preferred form of clamping device mounted on a round rail post.

Fig. 2 is a side elevation thereof.

Fig. 3 is a view similar to Fig. 1, showing the preferred form of device mounted on a square post.

Fig. 4 is a top plan view of a modified form of the clamping device mounted on a round post.

Fig. 5 is a side elevation thereof.

Fig. 6 is a view similar to Fig. 4 showing the modified form of device mounted on a square post.

Fig. 7 is a top plan view of the form of clamping device used at the ends of the cable 85 on the end posts of the guard rail.

Fig. 8 is a side elevation thereof.

As shown in Figs. 1, 2 and 3, the preferred form of my cable clamping device comprises a body portion 1, of desired length, having a 90 relatively short transverse projection 1^a at the center thereof, said projection 1^a having at its outer end a metal strap 1^b for attaching the device to the rail post P, which strap 1^b, if the device is to be mounted on a round post (Figs. 1 and 2) is preferably arcuate and curved to suit the radius of the round post upon which the device is to be mounted, but in case the device is to be mounted on a square post, (Fig. 3) the strap 1^b is preferably formed in an L-shape with one leg thereof disposed parallel to the longitudinal axis of the body portion 1, and the other leg disposed at right angles thereto, so that the device may be attached to a corner of such square post of any size. The outer ends of the strap 1^b are provided with perforations 1^c adapted for the passage therethrough of

the tap-bolts or screws 1^a which hold the device to the post. The plane of the longitudinal axis of the strap 1^b is preferably parallel with the longitudinal axis of the body portion 1.

5 The body portion 1 of the preferred form of clamping device, shown in Figs. 1, 2 and 3, is of suitable length, and is preferably substantially semi-circular in cross-section, the radius of the inner face thereof being equal to that of the cable C which is to be clamped thereto. The body portion 1 extends slightly more than half-way around the cable C, but no portion of the body 1 extends beyond the outer edge of the cable C or into the vertical plane tangent to the edge of the cable C opposite to the posts P, for the purpose hereinafter described.

10 The outer face of body portion 1 is preferably slightly tapered at both ends, and adapted to receive the correspondingly tapered relatively thick C-shaped members 1^c, which slidably engage said tapered ends and are driven over the tapered ends of the body to contract the body portion 1 around the cable C thereby frictionally binding the cable in the device, and preventing longitudinal or transverse movement of the cable C in the body portion 1.

15 20 25 30 35 40 45 As shown, no portions of the C-shaped members 1^c extend beyond the outer edge of the cable C, or into the vertical plane tangent to the edge of the cable C opposite to the posts P, so that when the cable is properly clamped in the device the latter presents no projection into the vertical plane of the tangent to outer edges of the cables C, whereby in case an automobile or other vehicle should collide with, or side-swi

40 45 50 55 60 cable guard-rail the vehicle may slide unobstructed past the fence posts P and cable clamps, and suffer no additional damage which would be caused by impact therewith, resulting in a violent, sudden stop.

The modified form of cable clamping device shown in Figs. 4, and 5 and 6 embodies the same principal feature of the device shown in Figs. 1, 2 and 3, in that no portion of the device projects into the vertical plane of the tangent to outer edge of the cable C, when such cable is secured in the device.

65 The body portion 2 of the modified form (Figs. 4-6) is somewhat shorter than the body 1 of the device shown in Figs. 1-3, but is provided with a longitudinal groove 2^a on its outer side face, said groove 2^a being substantially semi-circular in cross-section, and extending more than half-way around the cable C, the radius of curvature of said groove 2^a being the same as that of the cable C which is to be clamped therein, so that when the cable is inserted in said groove the outer edge of the cable projects beyond the outer edge of the body 2.

The body 2 is furthermore provided with a central recess 2^b extending the full length of the body 2 and extending into the semi-circular groove 2^a, whereby the upper and lower portions of the groove 2^a may be drawn together by means of a bolt 2^c extending through perforations 2^d in the body 2, said bolt having a nut thereon. As the nut is tightened the upper and lower portions of groove 2^a will be drawn together and contracted around the cable C securely binding the cable in the clamp.

70 75 80 85 On the inner end of body portion 2 is a strap 2^e, similar to strap 1^b shown in Figs. 1, 2 and 3, said strap 2^e being either arcuate to fit a round post, or L-shaped to fit a square post. Bolt 2^c is disposed between the groove 2^a and the strap 2^e, so that no portion of said bolt will project into the vertical plane tangent to the outer edge of the cable C.

90 95 100 105 The clamping device 3 used at each end of the cable C, shown in Figs. 7 and 8, is preferably U-shape in cross-section, the distance between the parallel legs 3^a thereof being preferably slightly less than the diameter of the cable C. Through the base of the device 3 is a perforation 3^b adapted to receive a tap-bolt or screw 3^c for fastening the device to the post. The base of the clamp is preferably widened as at 3^d to prevent the device from pivoting upon the post. The end of the cable C is preferably wrapped half-way around the end post and forcibly inserted between the legs 3^a of clamp 3, thereby binding the end of the cable in the device. In case the end post should be square instead of round (Fig. 7) the corners of the post in way of the cable could be notched or cut away to relieve the bending strain in the cable.

110 115 120 125 A cable guard-rail constructed with my novel cable clamping devices, will be strong, durable, and flexible, and can be readily erected by inexperienced workmen; the strain will be equally distributed throughout the entire line of posts thereby developing the full strength of the cable; the posts may be replaced at any point without interference with any other part of the guard-rail; the cable is positively supported at each post; the cable will shunt colliding vehicles back into the road and by reason of the fact that no portions either of the posts or cable clamping devices project into the vertical plane of the tangent to the edge of the cable opposite to the posts the guard-rail will do no damage to a vehicle which may side-swi

130 135 140 the guard rail at a point opposite a post. I do not limit my invention to the exact forms shown in the drawing, for obviously minor details may be made therein within the scope of the invention.

I claim:

1. A cable clamp comprising a body portion; means for mounting said body portion on a post; said body portion having a

groove in its face opposite to said supporting means of less depth than the diameter of the cable to be inserted therein; and means engaging the body portion opposite the groove for clamping the cable in said groove, no portion of the clamp projecting beyond the outer edge of the cable.

2. In a cable clamp as set forth in claim 1, the ends of said body portion being tapered outwardly, and said clamping means comprising members slidably engaging said tapered portions, no portions of said members projecting beyond the outer edge of the cable.

3. A cable clamp comprising an integral body portion; means for mounting said body portion on a post; said body portion having a substantially semi-circular groove in its face opposite to said supporting means, said groove being of less depth than the diameter of the cable to be inserted therein; and means engaging the body portion opposite the groove for contracting the body

around the cable; no portion of the clamp projecting beyond the outer edge of the cable, 25

4. A cable clamp of the character specified comprising an integral substantially C-shaped body portion adapted to extend slightly more than half way around a cable inserted therein; means for mounting said body portion on a post; and means engaging the outer edges of the body portion for contracting the body around the cable, no portion of the clamp projecting beyond the outer edge of the cable. 30 35

5. In a cable clamp as set forth in claim 4, the ends of said body portion being slightly tapered outwardly, and said contracting means comprising correspondingly tapered substantially C-shaped members slidably 40 engaging said tapered portions; no portions of said members projecting beyond the outer edge of the cable.

In testimony that I claim the foregoing as my own, I affix my signature.

JOHN C. NEVIUS.
